UNITED STATES PATENT OFFICE.

ALBERT W. ALBRECHT, OF ST. LOUIS, MISSOURI.

METHOD OF MAKING PISTON RINGS.

1,415,620.

Specification of Letters Patent.

Patented May 9, 1922.

Application filed October 20, 1919. Serial No. 332,105.

To all whom it may concern:

Be it known that I, ALBERT W. ALBRECHT, a citizen of the United States, residing at the city of St. Louis and State of Missouri, have invented a new and useful Method of Making Piston Rings, of which the following is a specification.

This invention relates to a method of making piston rings.

10 An object of the invention is to provide an improved method for manufacture of piston rings from metal bars by rolling or otherwise forming the bars, in such shape that when the bar is rolled or formed in 15 overlapping spirals, the ring wall will be of the same width all around.

Another object of the invention is to provide a novel method of forming rings from a non-circular ring blank by rolling the 20 blanks into circular shape, having one or more spiral turns.

From the following detailed description of the method of manufacture, taken in connection with the accompanying drawing, 25 my improvement may be clearly understood.

In the drawing,

Fig. 1 is a view of the metal bar from which the ring blanks are formed, before the same has been rolled or otherwise formed 30 into the ring blank.

Fig. 2 is a view of the ring blank from which the ring is formed.

Fig. 3 is a side elevation of the ring.

Fig. 4 is an elevation of the finished ring, 35 and

Fig. 5 is a view of the finished ring viewed from a point at right angles to the illustration in Fig. 4.

The ring blanks are formed from the bar 40 illustrated in Fig. 1, which bar is preferably rectangular in cross-section. The bar may be of any suitable metal.

The bar is first rolled into a metal strip or ring blank illustrated in Fig. 2. The bar 45 may be cold rolled or rolled after heating. After the rolling process has been carried out, the ring blank will have an intermediate body portion 1, which is tapered in opposite directions forming the tapered end 50 sections 2 and 3, terminating in knife edged extremities 4, and 5, respectively.

After the ring blank has been formed, as shown in Fig. 2, it is rolled into annular form, either in the cold state or under heat 55 as desired. The finished ring comprises

overlapping spirals, there being as many spiral turns as desired.

The line of taper in both directions from the intermediate body portion 1 is such that when the ring is rolled with its extremities 60 at diametrically opposite points, the combined width of the spirals will be equal throughout the circumference of the ring.

In forming the ring from the ring blank, the ring is so rolled that the adjacent edges 65 of the spirals will be in close contact with each other throughout the circumference of the ring, in order to close the gap and leave no space between the edges of the spirals.

It will be understood that the rings may 70 be made of varying diameters, and that the finished rings will have a diameter equal to the inner diameter of the cylinder in which it is intended for use.

By accurately forming the ring blank and 75 rolling it into annular shape, no finishing or grinding operation is required.

From the foregoing, it will be observed 80 that rings may be made by the improved method herein disclosed, very economically, and that the rings will be uniform throughout.

What I claim and desire to secure by Letters Patent is:

1. The method of making a one-piece piston ring, which consists in shaping a non-circular bar to form a rectilinear central portion of equal width throughout its length, and tapering end portions narrower than the central portion throughout their 85 length and each end portion being bordered on one side edge throughout its length by a rectilinear continuation of one of the side edges of the central portion and its opposite side edge being inclined from an intersection with said rectilinear continuation to an intersection with the opposite side edge of the central portion, and rolling said non-circular bar into annular form to place the inclined side edges of said end portions in 90 contact with the side edges of the central portion respectively, so that the completed ring will be of the same width throughout its circumference. 95

2. The method of making a one-piece piston ring, which consists in shaping a non-circular bar to form a central portion of equal width throughout its length and to form tapering end portions each of which is bordered on one side edge throughout its 100 105 110

length by a rectilinear continuation of one of the side edges of the central portion, and its opposite side edge being inclined from an intersection with said rectilinear continuation to an intersection with the opposite side edge of the central portion, and rolling said non-circular bar into annular form to place the inclined side edges thereof in contact with the side edges of the central portion so that the completed ring will be of the same width throughout its circumference.

3. The method of making a one-piece piston ring, which consists in shaping a non-circular bar to form a central portion of equal width throughout its length and to form tapering end portions each of which

is bordered on one side throughout its length by a rectilinear continuation of one of the side edges of the central portion, and its opposite side edge being inclined from an intersection with said rectilinear continuation to an intersection with the opposite side edge of the central portion, said inclined side edges being on opposite sides of the bar and in parallel planes, and rolling said non-circular bar into annular form with the inclined side edges toward each other and in contact with the side edges of the central portion so that the completed ring will be of the same width throughout its circumference.

ALBERT W. ALBRECHT.
